POSTURE METER

Fred S. Williams, Trumbull, Conn., assignor to
Dorothy C. Williams, Trumbull, Conn.

Application September 22, 1936, Serial No. 101,929

18 Claims. (Cl. 33—174)

This invention relates to new and useful improvements in testing or measuring apparatus and has particular relation to a means for measuring and indicating disalignment of the joints of the 5 human body.

An object of the invention is to provide an apparatus of the character stated and which is of simple construction, easy to operate and accurate.

Other objects and advantages will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:—

20 Fig. 1 is a top plan view of the present apparatus;

Fig. 2 is a side elevational view thereof with parts broken away;

Fig. 3 is a sectional view taken substantially along the line 3—3 of Fig. 1;

25 Fig. 4 is an enlarged detail sectional view through an edge portion of a platform employed;

Fig. 5 is an elevational view, on an enlarged scale, showing the details of a rod forming part of the apparatus; and

30 Fig. 6 is an enlarged detail sectional view showing a hingelike joint employed in the rod of Fig. 5.

Referring in detail to the drawing, the present apparatus, hereinafter referred to as a "posture meter", is shown as comprising a base generally designated 10. The base is a box-like structure including side walls 11, 12, 13 and 14 of which the walls 11 and 12 comprise respectively an end wall and the rear wall. Within the base in spaced relation to the end walls 11 and 13 are partitioning or supporting members 15 and 16 while substantially similar members 17 and 18 are within the base in spaced relation to the front and rear walls 14 and 12 respectively.

45 At the inner sides of and flush with the upper edges of the members 15, 16, 17 and 18 are braces 19. These braces together with the upper edges of the respective members, receive and removably support a platform 20 on which a patient may stand and as here disclosed a metal angle member 21 extends about the edge of such platform with its upper horizontal portion spaced slightly above the upper surface of the platform.

50 Foot position indicator strips 22, 23, 24 and 25 are disposed on the upper surface of the platform 20 and of these strips those numbered 22 and 23 extend between the front and rear edges of the platform and comprise a pair while the strips 24 and 25 comprise a second pair extending cross-

wise with respect to strips 22 and 23 and from end to end of the platform. The ends of the strips simply extend under the horizontal flanges of the angle members 21 so that each of said strips is laterally adjustable independent of the other 5 strips.

Braces 26 are located at the inner sides of the walls of the base and flush with the upper edges of such walls. Channel members 27 span the upper edges of the walls and also span the braces 26. Along one end the platform is spaced from the channel members leaving a slot 28 and along its rear edge the platform is also spaced from the channel member thereby providing a slot 29.

Between the member 18 and the rear wall 12 the bottom 30 of the base is provided with guide rails 31 and 32. A similar guide rail 33 is carried by a part 34 secured to the upper portion 18 and yet another guide rail 35 is carried by the brace 26 on the rear wall 12 of the base. A pair 20 of blocks 36 and 37 are mounted on the guide rails 31 and 33 for independent adjustment along the same and each block includes a portion extending under the slot 29 and carrying a socket member 38 extending upwardly through such slot 25 for the reception of vertically extending rods 39 and 40 respectively. Obviously, by engaging the members 38 the blocks may be shifted, independently of one another, along the guide rails 31 and 33.

30 Mounted on the guide rails 32 and 35 are blocks 41 and 42 adjustable along such rails independent of one another and independent of the blocks 36 and 37. A horizontal slot 43 is formed in the rear wall 12 and may, if desired, be bound by a 35 facing strip 44. Extending through such slot and into the blocks 41 and 42, or secured to such blocks in any other suitable manner, are shanks 45 and 46 provided respectively with hand pieces 47 and 48 adapted to be manipulated to move the shanks 40 along the slot 43 and thus adjust the blocks 41 and 42 along the rails 32 and 35.

Carried by the blocks 41 and 42 and extending upwardly through the slot 29 are socket members 49 each at its upper end mounting the similar rods 50 and 51, a detailed description of one of which will, it is believed, suffice for both. As shown best in Fig. 5 the rod 50 is sectional comprising a plurality of hinge-like joints 52, 53 and 54 and comprising telescopic joints 55, 56 and 57 arranged one above each of said hinge-like joints. The sections have frictional engagement at the telescopic joints so that they will remain in the desired positions of vertical adjustment and it will be plain that owing to the telescopic joints 55 the hinge-like joints may be disposed closer together or farther apart as desired. The purpose of this arrangement will later be fully set forth.

55 Preferably, above the base the rod 50 progressively decreases in diameter and each of the hinge-

60 60

- like joints decreases in size as it is a step further above the base. This is to make the apparatus of better appearance and has nothing to do with its functioning and, if desired, the rod may be 5 of the same diameter throughout its length and all of the hinge-like joints may be of the same size. As the hinge-like joints are all of the same construction, a description of the joint 52 alone will, it is believed, be sufficient.
- 10 Referring more particularly to Figs. 5 and 6 the joint 52 comprises a socket member 58 receiving the upper end portion of the vertical socket member 49 and a socket member 59 receiving the lower end portion of the rod section 15 60. Members 58 and 59 are connected by a pivot 61 and have some frictional engagement in their portions about the pivot whereby they will remain in various positions of angular adjustment. Screws 62 secure a plate 63 to the joint section 20 58 and this plate is graduated along its upper edge 64 and such graduations are to be read in conjunction with a pointer 65 carried by the rod section 60. With this arrangement any angular relationship between the rod sections 49 and 60, 25 due to movement of the joint section 59 relative to the joint section 58, will be indicated on the plate 63. The purpose of this arrangement at the various hinge-like joints will later be set forth.
- Between the end wall 11 and the inner member 15 a guide rail 66 is mounted on the bottom 30 of the base and a companion guide rail 67 is mounted on the brace 26. Adjustable along these guide rails is a block 68 to which is attached a shank 69 extending through a slot 70 in wall 11 and about which slot may be one of the facing 35 strips 44. On the outer end of the shank 69 is a hand piece 71 by means of which the block 68 may be moved or adjusted along the guide rails 66 and 67. Carried by the block 68 and extending 40 up through the slot 26 are a pair of rods 72 and 73 of which the rod 72 is solid or without joints as in the case of the rods 39 and 40 while the rod 73 is of the same construction as the rods 50 and 51 being provided with hinge-like 45 joints and with telescopic joints to provide for adjustments as will appear. Obviously, the rods 72 and 73 being both mounted by the block 68 must be adjusted along the slot 26 together on manipulation of the hand piece 71.
- 50 In using the apparatus a patient stands on the platform 20 with his heels or toes toward the slot 29. The guide strips 24 and 25 are positioned to be under the heels and the balls of the feet of the patient and the strips 22 and 23 are adjusted 55 the distance apart that the patient's feet should be. Then the patient stands with his feet along the strips 22 and 23 and with the balls of his feet on the strip 25 and with the strip 24 under and in line with his ankle joints. Next the blocks 60 36 and 37 are adjusted to locate the rods 39 and 40 extending upwardly at the rear or front of the patient's legs and the blocks 41 and 42 are adjusted to bring the rods 50 and 51 into alignment with the rods 39 and 40.
- 65 Thereafter, the block 68 is shifted to move the rods 72 and 73 along the slot 26 to align such rods with the side of the patient's leg. This adjustment also aligns the rods 72 and 73 with the strip 24. This correctly positions the parts 70 and from the side, the rod 72, which may be in one piece, should align with the various joints of the patient's frame, as the ankle, knee and hip. Similarly as viewed from the rear or front the same joints of the frame should align with the 75 rods 39 and 40 carried by the blocks 36 and 37.

Now the adjustable rods 50, 51 and 73 are adjusted to locate a hinge-like joint at the ankle, knee and hip of the patient and if desired, the rods may include additional hinge-like joints and may extend for the length of the body of the patient having, for example, a hinge-like joint for the shoulder. Due to the telescopic joints between the various hinge-like joints any necessary adjustments may readily be made so as to dispose a hinge like joint in alignment with each 10 joint of the patient's frame.

Now the operator adjusts the various hinge-like joints to have the portions of the rods between such joints follow the bones of the patient's frame. For example, the hinge-like joint 52 at 15 the ankle is adjusted to have the rod section 60 angularly related to the rod section or portion 49 whereby the section 60 in the case of the rod 73 may be extending forwardly at an incline or rearwardly as the case may be. The various sections of the rods 50 and 51 may need no adjustment in which case the frame structure of the patient is aligned but if such frame is not aligned then the proper adjustments are made to have the various sections of such rods between the 25 hinge-like joints follow the various bone sections of the patient's frame.

When all adjustments have been made the adjustable rods 50, 51 and 73 have their various sections or the portions between their hinge-like 30 joints following the frame of the patient and such rods show whether the patient's frame is properly aligned and if not show the disalignment exactly as it exists. The scales at the hinge-like joints show the degree of disalignment in each 35 case and with such information at hand the proper authority may advise the patient how to correct the fault. The rods 39, 40 and 72 are not essential and may be omitted although such rods are of assistance in that they may be used 40 as indicators against which to read the adjustments of the rods 50, 51 and 73.

The rods 50, 51 and 73 between the hinge-like joints are provided with graduations as at 74 in Fig. 5. With this arrangement after proper 45 vertical adjustments have been made to bring any particular hinge-like joint opposite a joint in the patient's frame the height between the two hinge-like joints will be readily apparent. Rivet 61 may be hollow whereby an operator may pass 50 a suitable marker through it to mark the patient's joint and to make sure that the hinge-like joint is really aligned with the joint of the patient's frame.

Having thus set forth the nature of my invention, what I claim is:—

1. In a posture-meter, a base including a platform on which a patient may stand, supporting means on the base, a vertically extending rod carried by said means and projecting above said platform, and a joint in said rod above the platform whereby portions of the rod may be disposed in angular relationship.
2. In a posture-meter, a base including a platform on which a patient may stand, a supporting means on the base, a rod extending vertically from said means and projecting substantially above said platform, a joint in said rod above said platform whereby a portion of the rod may be disposed angularly, and a vertically adjustable 65 connection in said rod at the upper side of said joint.
3. In a posture-meter, a base including a platform on which a patient may stand, a supporting means on the base, a rod extending vertically 70 from said means and projecting substantially above said platform, a joint in said rod above said platform whereby a portion of the rod may be disposed angularly, and a vertically adjustable 75 connection in said rod at the upper side of said joint.

from said means and projecting substantially above the platform, and said rod above said platform including a series of independently vertically adjustable sections and an angularly adjustable joint between each of said sections.

5. In a posture-meter, a base including a platform on which a patient may stand, a supporting means on said base, means whereby said supporting means is adjustable along an edge of the platform, a rod extending vertically from said means, and a joint in said rod whereby portions thereof may be located in angular relationship.

10. In a posture-meter, a base including a platform on which a patient may stand, supporting means on the base, a vertically extending rod carried by said means and projecting above said platform, a joint in said rod above the platform whereby portions of the rod may be disposed in angular relation, and means on said rod at said joint to indicate the degree of the angular relationship of said portions.

15. In a posture-meter, a base comprising a box-like structure including a removable platform on which a patient may stand, a block in the base at one edge of the platform and adjustable therealong, a rod carried by said block and extending vertically therefrom, and a joint in said rod whereby portions thereof may be disposed in angular relation.

20. In a posture-meter, a base comprising a box-like structure including a platform on which a patient may stand, a pair of blocks in said base at one edge of the platform and independently adjustable therealong, a rod carried by each of said blocks and extending vertically therefrom, and a joint in each of said rods whereby portions thereof may be disposed in angular relationship.

25. In a posture-meter, a base comprising a box-like structure including a platform on which a patient may stand, a pair of blocks in said base at one edge of the platform and independently adjustable therealong, a rod carried by each of said blocks and extending vertically therefrom, and a joint in one of said rods whereby portions thereof may be disposed in angular relationship.

30. In a posture-meter, a base including a platform on which a patient may stand, a supporting means projecting substantially above said platform on the base, a pair of rods above the platform extending vertically from said means, a joint in one of said rods whereby a portion of said rod may be disposed angularly, and a vertical adjustable connection in said rod at the upper side of said joint.

35. In a posture meter, a base including a platform on which a patient may stand, a supporting means on the base, means whereby said supporting means is adjustable along an edge of said platform, a pair of rods extending vertically from said means, a joint in one of said rods whereby a portion thereof may be disposed angularly, and a vertical adjustable connection in said rod at the upper side of said joint.

40. In a posture-meter, a base comprising a box-like structure including a platform on which a patient may stand, a block in the base at one edge of the platform and adjustable therealong, a pair of blocks in the base at another edge of the platform and independently adjustable therealong, a vertically extending rod carried by each

of said blocks and projecting above the platform, and a joint in each of said rods whereby portions thereof may be disposed in angular relationship.

45. In a posture-meter, a base comprising a box-like structure including a platform on which a patient may stand, a block in the base at one edge of the platform and adjustable therealong, a pair of blocks in the base at another edge of the platform and independently adjustable therealong, a vertically extending rod carried by each of said blocks and projecting above the platform, a joint in each of said rods whereby portions thereof may be disposed in angular relationship, foot position indicator strips on the upper surface of said platform, said strips arranged in pairs with the strips of one pair crossing those of the other pair, and the strips of the said pairs adjustable laterally toward and from one another.

50. In a posture-meter, a base comprising a box-like structure including a platform on which a patient may stand, a pair of blocks in said base at one edge of the platform and independently adjustable therealong, a rod carried by each of said blocks and extending vertically therefrom, a joint in each of said rods whereby portions thereof may be disposed in angular relationship, and guide rails in said base and along which said blocks are adjustable.

55. In a posture-meter, a base comprising a box-like structure including a platform on which a patient may stand, a pair of blocks in said base at one edge of the platform and independently adjustable therealong, a rod carried by each of said blocks and extending vertically therefrom, a joint in each of said rods whereby portions thereof may be disposed in angular relationship, and guide rails in said base and along which said blocks are adjustable.

60. The combination as in claim 11 including a one piece indicator rod associated with each of said jointed rods.

65. In a posture meter, a base including a platform on which a patient may stand, a supporting means on the base, means whereby said supporting means is adjustable along an edge of said platform, a rod extending vertically from said means, joints in said rod whereby portions thereof may be disposed angularly, a vertically adjustable connection in said rod at the upper side of each of said joints, and graduations on said rod whereby after each vertical adjustment the distance between the joints may be readily determined.

70. In a posture-meter, a base comprising a box-like structure including a platform on which a patient may stand, a block in the base at one edge of the platform and adjustable therealong, a pair of blocks in the base at another edge of the platform and independently adjustable therealong, a vertically extending rod carried by each of said blocks and projecting above the platform, a joint in each of said rods whereby portions thereof may be disposed in angular relationship, foot position indicator strips on the upper surface of said platform, and said strips adjustable laterally toward and from one another.

75. In a posture-meter, a base comprising a box-like structure including a platform on which a patient may stand, foot position indicator strips on the upper surface of said platform, said strips arranged in pairs with the strips of one pair crossing those of the other pair, and the strips of the said pairs adjustable laterally toward and from one another.

80. In a posture-meter, a base comprising a box-like structure including a platform on which a patient may stand, a pair of foot position indicator strips on the upper surface of said platform, and said strips adjustable laterally toward and from one another.

FRED S. WILLIAMS.
